Inventor:
John Harrar

UNITED STATES PATENT OFFICE.

JOHN HARRAR, OF PHILADELPHIA, PENNSYLVANIA.

SKATE-FASTENING.

Specification forming part of Letters Patent No. 42,472, dated April 26, 1864.

To all whom it may concern:

Be it known that I, JOHN HARRAR, of the city of Philadelphia, and State of Pennsylvania, have invented a new and useful Improvement in Skate-Fastenings—to wit, on that mode wherein a flat plate (as represented in Figure 1 of the accompanying drawings) is employed, having made through it holes *s s* for the reception of screws, which are necessary to fasten it to the heel of a boot, also an elongated aperture, *a*, to receive and hold the counterpart or nipple *n*, attached to a skate, as shown at Fig. 2; and I do hereby declare that the following is a full and exact description of my invention, reference being had to the accompanying drawings, and to the letters of reference, in which—

Fig. 3 is a perspective view of a cylinder, having around its entire external sides a screw-thread, *t t*, said screw-thread having several notches, *v v*, made across it to enable it to cut its way, and a circular cavity, *c*, leading endwise about three-fourths way through, the employment of which, instead of the above-described flat plate, (but having a like elongated aperture leading through its other fourth part, as *a* in the perspective view, Fig. 4, and opening into the cavity *c*, as shown in the vertical section *e r*, Fig. 6, corresponding with the line *e r* of the plan Fig. 5,) when screwed into a hole made in the heel of a boot, will answer all the purposes of said flat plate, and has the advantage of a more ready adjustment, can be graduated as the leather wears, is applicable to the smallest heel, and may be readily removed and the hole stopped.

To enable others skilled in the art to make my invention, I will proceed to describe its construction.

On the end of a rod of iron or other hard metal, of five-eighths of an inch in diameter, I cut a screw-thread, *t t*, (of from twenty to twenty-four threads to the inch,) for any distance, tapering it slightly for about two revolutions at the end. From this end I drill a cavity, *c*, of seven sixteenths of an inch in diameter, and five-sixteenths in depth, then make a cut around and nearly through the rod, at the distance of seven-sixteenths of an

inch from the end. I then screw the end into a block of hard wood for a short distance, and sever it from the rod. I now have a short cylindrical screw with a cavity in it held fast in the block, the end of which I level off. From the end thus leveled and opening into the cavity *c*, I drill and shape an elongated aperture, *a*, to fit the counterpart or nipple *n* attached to the skate, then remove it from the block, and cut the notches *v v* across the thread.

To make use of my invention, I fasten it to the boot by boring a hole in the heel, with a nine-sixteenths of an inch center-bit, then enter the slightly tapered end of the cylinder, and in the elongated aperture *a* insert the counterpart or nipple *n*, attached to the skate, and with the skate as a lever screw the cylinder until about flush with the heel, stopping when the skate is at right angles with the length of the boot. To lock the cylinder and the counterpart together, let the nipple of the counterpart pass through the aperture into the cavity, and turn the skate to its proper place under the boot, when it will be held fast by means of the neck of the counterpart being caught by the sides of the elongated aperture.

What I claim as my invention, and desire to secure by Letters Patent, is—

The combination of a metallic cylinder, Fig. 3, screw-thread *t t*, notches *v v*, and cavity *c*, which, when employed instead of the flat plate shown at Fig. 1, but having a like elongated aperture, *a*, opening into the cavity *c*, will obtain for the said elongated aperture a more ready adjustment, graduation, removal, and require less space, substantially for the purpose described, not meaning to make any claim to the elongated aperture *a* or the counterpart *n*, attached to the skate, when used separately from my invention.

Witness my hand the 14th day of March, A. D. 1864, in the city of Philadelphia, Pennsylvania.

JOHN HARRAR.

In presence of—

JOHN L. FREDERICK,
M. L. FREDERICK.
